HOSIERY AND METHOD OF MAKING THE SAME

Dwight J. Harris, Philadelphia, Pa.

Application January 4, 1938, Serial No. 183,275

5 Claims. (Cl. 66—173)

The present invention relates to hosiery and the method of making the same. More particularly, the invention pertains to knitted stockings, and has for one of its main objects the provision of a stocking consisting of weft knitted fabric sections associated in a novel manner to impart distinctive characteristics to the finished product.

Another important object of the invention resides in the provision of a stocking consisting of at least two sections so arranged with respect to each other that "runs" occurring in one of said sections are prevented from passing into the remaining section.

Still another object of the invention contemplates the provision of a stocking having a welt constructed of weft knitted fabric, so disposed that the wales thereof are directed circumferentially of the stocking whereby a "run" occurring in said welt will travel around, and not lengthwise of, the stocking. Thus, such a run cannot pass beyond the welt and enter in the leg portion where it would become visible.

The invention is especially characterized by the provision of a knitted stocking constructed of two united adjacent sections, the wale loops of one section being disposed to extend in a direction at substantially right angles to that of the wale loops of the remaining section.

It is a specific feature of the invention to provide a stocking having a welt fabric folded wale-wise to form a double ply welt and a leg fabric interknitted with the selvedge edges of the folded welt whereby the wale loops in the welt fabric will extend circumferentially of the stocking, whereas the wale loops of the leg fabric will extend longitudinally of said stocking.

Other important objects and advantages of the invention will be in part obvious and in part pointed out hereinafter.

In order that the invention and its mode of operation may be readily understood by those skilled in the art, I have in the accompanying drawings and in the detailed description based thereupon, set out possible embodiments of the invention.

In these drawings:

Figure 1 diagrammatically illustrates a stocking made in accordance with the invention.

Figure 2 is a diagrammatic representation of a flat knitted welt fabric construction.

Figure 3 is an enlarged diagrammatic representation of the welt fabric connected to the leg fabric of the stocking.

Figure 4 is a view similar to Figure 3, illustrating the mode of knitting the welt fabric.

Figure 5 diagrammatically illustrates a modification of the invention.

Figure 6 diagrammatically illustrates a further modification of the invention.

Figure 7 is a diagrammatic representation of the construction of the welt fabric and its extension.

Figure 8 diagrammatically shows a circular knitted welt construction.

Figure 9 is a diagrammatic representation of the embodiment of the invention in the toe structure of a stocking.

Having more particular reference to the drawings wherein like characters of reference will designate corresponding parts throughout, I have shown in Figure 1 a finished knitted stocking 1 consisting of a welt fabric 2, and a leg fabric 3 including the instep 4, the heel 5, sole 6, and toe 7. As will clearly appear from Figure 1, the wale loops 8 of the welt fabric extend in a direction at substantially right angles to the wale loops 9 of the leg fabric 3, that is, the wale loops 8 of the welt extend transversely or circumferentially of the stocking, whereas the wale loops 9 extend longitudinally or lengthwise of the stocking. In this manner, should a run occur in any part of the welt, such a run will travel circumferentially of the stocking and not towards and into the leg where it would be visible.

The welt may be of any desired construction and may be connected to the leg in any suitable manner. However, in accordance with the showing made herein, I prefer to proceed as follows:

The welt fabric 2 is started in the usual manner on a suitable flat knitting machine. As will more clearly appear from Figures 2 and 4, during the knitting of the series of courses 10, a loop 11 in the medial portion of each course is transferred to an adjacent loop, as represented at 12, so that an open wale 13 is formed to extend longitudinally of the fabric for the purpose to be later specified. The fabric is knitted in a length sufficient to equal the circumference of the stocking intended to be made.

Although individual welt fabrics may be made, I prefer to knit several of them in a continuous strip from which each welt may subsequently be cut. In making a continuous strip of welt fabric, it is advisable to form a loose course 14 at regular intervals, thus providing a clear demarking and cutting line between each individual welt. The loose course 14 may be preceded and followed by one or more plain courses 15.

In making the stocking, a completed welt fabric is folded along the open wale 13 so that the opposite selvedge edges 16 thereof are brought in overlapping relation, said open wale thus forming a finished edge 17 resembling an ordinary picot edge.

The overlapping selvedge edges 16 may then be topped upon the needles of an ordinary full-fashioned knitting machine and the leg fabric 3 knitted thereon in the customary manner, thus forming an interknitted connection between the welt and the leg, as more clearly represented at 17' in Figures 1 and 3 of the drawings.

The marginal edges of the interconnected welt and leg fabrics may be looped together in the ordinary fashion to form the back seam 18, the provision of the plain courses 15, which are then at the marginal edges of the welt, forming a good selvedge for the looping operation.

It will be understood that instead of interknitting the leg 3 with the welt 2, in the manner hereinbefore specified, the welt may be attached to a completed leg by sewing, stitching, looping, or like appropriate operations.

In stockings of the type to which the present invention pertains, it is sometimes found desirable to construct the welt with an extension projecting to a point either above or below the knee in order to reinforce the upper part of the stocking against strains. The present invention accomplishes this purpose by providing the construction illustrated in Figures 5 and 6, Figure 5 showing the welt 2a formed with a relatively short extension 18 connected to the stocking leg 3a at a point approximately above the knee, and Figure 6 showing the welt fabric 2b formed with a relatively long extension 19 connected to the stocking leg 3b at a point approximately below the knee.

It will be noted that in both instances the wales 20 of the welt fabric extension 18 or 19 extend in the same direction as the wales 21 of the welt and at right angles to the wales 22 of the leg fabric 3a or 3b.

The mode of knitting the fabric to form a welt and its extension will be understood upon reference to Figure 7 wherein is diagrammatically shown a fabric blank 23 which may be knitted in the same manner as the welt fabric 2 illustrated in Figure 2, with the exception that it is of greater width and that the transfer of the single loop to form an open wale 24 is made in one end portion of the fabric. A number of fabric blanks, such as blank 23, may also be knitted in a continuous strip from which the individual blanks, separated by spaced loose courses 25, may subsequently be cut. The cut blank may then be folded along the open wale 24 so that the selvedge edge 26 lies substantially in the position indicated by the dotted line 27 and suitably secured by means of a looping, sewing, or stitching operation to the main body of the blank 23 to form the double ply welt provided with a finished edge 17a or 17b, as illustrated in Figures 5 and 6 respectively.

The other selvedge edge 28 of the blank 23 is then topped upon the needles of a full-fashioned knitting machine and the leg fabric 3a or 3b knitted as a continuation thereof.

In Figure 8 of the drawings, I have shown a further modification of the invention in that the welt fabric, instead of being made on a flat knitting machine, is knitted on a circular knitting machine. When knitting the circular fabric blank 30, a stitch is preferably dropped at oppo-

site sides of the blank to provide a pair of diametrically opposed open wales 31 and 32 respectively, for the purpose of providing a fold line so that, upon folding the blank therealong, 5 a double ply welt may be had. With the folding of the blank, a wale on each side of one of the open wales 31 or 32 may be topped upon the needles of a flat knitting machine and a full-fashioned leg knitted thereonto in the usual manner, the remaining open wale constituting a finished edge at the upper portion of the stocking.

It will be understood that when the welt blank 30 is connected to the leg in the manner above stated, the wales 33 thereof will extend in a direction at substantially right angles to the wales of the leg and, therefore, a run occurring in said welt will extend circumferentially of the stocking and not towards the leg.

A number of circular knitted fabric blanks 30 20 may be made continuously, each blank being separated by means of distinctive courses, such a loose course providing guide lines 34 for the cutting of the individual blanks.

As shown in Figure 9, the invention is also applicable to a toe construction. In accordance with this modification of the invention, a toe patch 35 having its wales 36 running transversely is suitably attached to the foot portion 37 of the stocking, the wales 38 of which run longitudinally. In other words, the wales of the toe substantially parallel the courses of the leg and foot. It will be understood that this latter construction may be had by knitting in the usual manner the leg and foot portions of a stocking blank 35 down to the point where the usual toe generally begins. At that point, the knitting is terminated, whereupon the blank may be removed from the machine and a section of separately knitted fabric united to the end of the foot portion of the blank by looping, stitching, or sewing thereto one of the selvedge portions of said section which may subsequently be cut to shape prior to the formation of the seam connecting the free edges of the blank to complete the stocking.

45 Because of this construction, it will be appreciated that a run occurring in the toe 35 will not pass into the leg since it will follow the direction of the wale in which the run occurs.

It is to be understood that the invention is 50 capable of other modifications and, therefore, any modifications coming within the scope of the subjoined claims are to be considered within the spirit of the invention.

What I claim is:

1. The method of making stockings, comprising: weft knitting a fabric blank; folding a section of said blank walewise; securing one selvedge edge of the folded section to an intermediate portion of the blank; and knitting a leg fabric onto the free selvedge edge of said blank.

2. A knitted stocking comprising: a welt consisting of a flat knitted fabric blank having the loops of a wale of one of its selvedge portions secured to the loops of a wale in the intermediate portion of said blank; and a stocking leg having the loops of one of its courses connected to the loops of a wale of the other of the selvedge portions of said blank.

3. A knitted stocking comprising: a welt consisting of a flat knitted fabric blank having the loops of a wale of one of its selvedge portions secured to the loops of a wale in the intermediate portion of said blank; and a stocking leg 75 having the loops of one of its courses knitted

onto the loops of a wale of the other of the selvage portions of said blank.

4. A knitted stocking comprising: a unitary welt and welt extension consisting of contiguous plain weft knitted fabric, the wales of said combined welt and welt extension extending circumferentially of the stocking; and a leg portion consisting of plain weft knitted fabric, the wales of said leg fabric extending longitudinally of the stocking.

5. A stocking comprising: a unitary double ply welt and a single ply welt extension consisting of contiguous plain weft knitted fabric, the wales of said combined welt and welt extension extending circumferentially of the stocking; and a leg portion consisting of plain weft knitted fabric the wales of said leg fabric extending longitudinally of the stocking.
